UNITED STATES PATENT OFFICE.

SAMUEL YEANY STOCKAMORE, OF GLOVERSVILLE, NEW YORK.

WINDING-MACHINE.

1,186,144.

Specification of Letters Patent.

Patented June 6, 1916.

Application filed April 22, 1915. Serial No. 23,165.

To all whom it may concern:

Be it known that I, SAMUEL YEANY STOCKAMORE, a citizen of the United States, residing at Gloversville, in the county of 5 Fulton and State of New York, have invented certain new and useful Improvements in Winding-Machines; and I do declare the following to be a full, clear, and exact description of the invention, such as will enable others skilled in the art to which it 10 pertains to make and use the same.

My invention relates broadly to improvements in the class of winding and reeling and specifically to a machine designed for 15 winding material delivered from a welt-cutting machine or the like, although its application need not be limited to this use.

The object of the invention is to improve upon the general construction of machines of 20 this class to such an extent as to provide a very simple device, yet one which will be very efficient in operation and will possess a number of advantageous features.

To this end, the invention resides in certain novel features of construction and combination of parts hereinafter described and more particularly pointed out in the appended claim.

In describing the invention, I shall refer 30 to the accompanying drawings wherein like reference characters designate corresponding parts throughout the several views, and wherein:

Figure 1 is a side elevation of the winding mechanism showing its application to a 35 welt-cutting machine; Fig. 2 is a top plan view of the construction seen in Fig. 1, parts being disclosed in horizontal section; Fig. 3 is a front end view of the winding machine 40 proper; Fig. 4 is a vertical transverse section thereof as seen along the plane designated by the line 4—4 of Fig. 1; Fig. 5 is a vertical longitudinal section taken on the plane indicated by the line 5—5 of Fig. 3; Fig. 6 is a detail vertical transverse section 45 taken on the plane indicated by the line 6—6 of Fig. 1, parts being shown in elevation; Fig. 7 is a view similar to Fig. 6, but showing the driving wheel and parts closely associated therewith in section; Fig. 8 is a detail horizontal section taken on the plane of 50 the line 8—8 of Fig. 3; Fig. 9 is an enlarged detail vertical section showing more particularly the means of securing the reels upon the spindles, and Fig. 10 is a vertical transverse section as viewed along the plane

indicated by the line 10—10 of Fig. 1, this view illustrating a tensioning device preferably employed in conjunction with the other features to be described.

In these drawings, constituting a part of the application, a welt-cutting machine M is shown including any preferred form of table T having guides G between which the sheet S of leather or the like is passed, the machine M being also equipped with rollers R at its opposite ends over which the sheet S passes, with a box B in which the sheet S is normally disposed, and with a pair of appropriate driven cutters C which slit the sheet longitudinally into a plurality of welts W. These welts pass over the rear-most roller R and then extend downwardly beneath a number of tensioning devices D here shown in the form of weights 60 slidable vertically upon upright guide rods GR, the latter being disposed in two longitudinally spaced transversely extending rows. Each of these rows is formed of a number of pairs of guide rods GR, and these pairs of the 65 two rows are disposed in staggered relation. By this means, the tensioning devices D are allowed to move vertically without abutting each other.

From the devices D, the welts W rise over 70 an additional roller R' mounted upon upright posts P or the like and disposed immediately in rear of said devices, it being evident from the drawings that the latter are located immediately in rear of the machine 75 M. The welts W then continue through a plurality of pot eyes 1 to reels 2, one guide being disposed adjacent each reel.

The pot eyes 1 are disposed one at each 80 end of a plurality of vertically spaced transversely disposed horizontal rods 3, these rods being mounted for reciprocation in 85 bearings 4 carried by the two spaced upright side plates 5 of a supporting structure. All of the rods 3 are rigidly connected to a single upright bar 6 which carries 90 between its ends a stud 7 or the like passing through a slot in the upper end of an oscillatory lever 8, this lever being fulcrumed 95 between its ends as seen at 9 to an appropriate rigid member 10, while its lower end is pivotally connected to the inner end of a horizontal reciprocatory link 11, the latter being mounted in appropriate bearings and being provided with anti-friction rollers 12 100 or the like engaging opposite points on the edge of a heart-shaped cam 13. This cam 105

is shown in the accompanying illustration as provided with a gear 14 which may be rotated by a pinion 15, although it will be evident that any preferred means could well be provided for driving said cam. The result of the construction just described, is slow reciprocation of the guides 1, thereby correctly positioning the numerous welts W upon the tubular reels 2.

10 The aforesaid reels 2 are disposed one on each end of a plurality of transverse vertically spaced horizontal spindles 16 which are rotatably mounted in bearings 17 carried by the two side plates 5, the central portions of the numerous spindles 16 being thereby extended across the space between these plates. These central portions are provided with grooved pulleys or the like 18 over which and a number of idlers 19 likewise disposed between the two plates 5, a belt 20 passes. This belt is likewise passed over upper and lower grooved pulleys 21 and 22 which are disposed in rear of the plates 5, and around a main driving pulley 23 which is secured to a transversely disposed driving shaft 24, said shaft being extended through openings in the lower end portions of the side plates 5 and being rotatably mounted in any appropriate type of bearings.

30 In order to rotate the shaft 24, the grooved driving wheel 25 is provided, this wheel being loose upon the shaft, but having a yieldable connection therewith by the provision of friction rings 26 interposed between the wheel 25 and a friction disk 27 which is affixed to the shaft 24. To accurately control the amount of friction existing between the wheel 25 and disk 27, or 40 rather between the two rings 26 carried thereby, the hub of the wheel 25 remote from the disk 27 is disposed against a thrust bearing 28 surrounding the shaft 24 and adjustable inwardly by the provision of a nut 45 29 threaded on said shaft.

50 The yieldable connection between the driving wheel 25 and the shaft 24 is essential, since with said driving wheel rotating at a uniform speed, and with the increasing of the winding area of the reels as the welts are wound thereon, it becomes necessary to provide some such construction whereby the numerous reels are allowed to rotate at less speed than the shaft 24. Otherwise, such 55 strain would be placed upon the welts as to cause breakage thereof. However, if it is found that the reels 18 are not rotating as fast as they should, the friction existing between the rings 26 may be increased by 60 proper actuation of the nut 29, thus establishing a more rigid connection between the driving wheel 25 and the shaft 24.

65 While the various spindles 16 and the reels 2 are being rotated to wind the welts on the latter, the guides 1 are being reciprocated

longitudinally of said reels to an extent to properly guide said welts thereon, all parts of the machine being operated in timed relation. If desired, the cam 13, and the cutters C may be driven from the driving 70 shaft 24. It will be evident, however, that independent means may well be employed for these purposes.

In removably securing the reels 2 upon the opposite ends of the spindles 16, said ends 75 are externally threaded as seen at 30 for the reception of nuts 31, such nuts being then disposed in contact with the outer ends of the tubular reels 2 and thereby forcing the latter into binding frictional contact with 80 stop disks 32 which are secured to the intermediate portions of the spindles 16 adjacent the bearings 17. By this simple detail of construction, it will be evident that the numerous reels 2 may be removed as they 85 are filled to their utmost capacity and that empty reels may be easily disposed operationally upon the machine.

90 From the foregoing description, taken in connection with the accompanying drawings, it will be evident that I have provided a very simple machine for carrying out the object of the invention, yet that the same will be efficient in operation and will possess a number of highly advantageous features. 95

Particular emphasis is laid upon the provision of the plurality of reciprocatory rods 3 actuated simultaneously by the single connecting bar 6 and the members associated therewith, upon the disposition of the pulleys 18, 19 and 23 between the side plates 5, 100 whereby they are housed as well as operationally supported, and upon the unique manner of detachably securing the reels 2 upon the spindles 3, these features being the most 105 salient of the machine.

110 In the foregoing, I have described certain specific details of construction for accomplishing probably the best results, and in the drawings have shown such details, but it will be evident that I need not be limited thereto otherwise than as set forth in the following which I claim as my invention:

115 A winding machine comprising an upright post-like support, a plurality of vertically spaced horizontal shafts revolvably mounted on said support and extending in opposite directions beyond the same, reels on the ends of the shafts, means engaging the centers of said shafts for driving the same, 120 bearings projecting forwardly from the support in advance of the several shafts, a plurality of horizontal vertically spaced rods slidably mounted in said bearings and disposed parallel to the shafts with their 125 ends spaced laterally from the reels, pot eyes carried by said ends of the rods, an upright rigid bar crossing the centers of the rods, clamps carried by said bar and securing it rigidly to the rods, a stud projecting rear- 130

wardly toward the support from the center of the bar, an upright lever confined between said bar and the support and fulcrumed between its ends to the latter, said lever having its upper end formed with a vertically elongated slot receiving the stud therein, and means connected with the lower end of the lever for oscillating the latter.

In testimony whereof I have hereunto set my hand in presence of two subscribing witnesses. 10

SAMUEL YEANY STOCKAMORE.
